Inventor,

Sidney C. Fisher;

By *A. Blipham*,
attorney.

UNITED STATES PATENT OFFICE.

SIDNEY C. FISHER, OF MEDFORD, MASSACHUSETTS.

FIRE-DOOR.

1,308,006.

Specification of Letters Patent. Patented June 24, 1919.

Application filed July 30, 1917. Serial No. 183,399.

To all whom it may concern:

Be it known that I, SIDNEY C. FISHER, a subject of the King of Great Britain, and a resident of Medford, in the county of 5 Middlesex and Commonwealth of Massachusetts, have invented certain new and useful Improvements in Fire-Doors, of which the following is a full, clear, and exact specification.

10 This invention relates to means for controlling through variations in temperature various kinds of closing devices, as fire doors, vertical shutters, balanced doors, safety elevator doors, fire curtains, fire shutters on exterior of buildings, doors in offices, stores and banks for safety and private reasons, exit doors in public buildings, trap doors, and the like, the invention being particularly disclosed as applied to fire doors.

20 My invention has for its objects the construction of electrically controlled means for holding doors open with a normally closed circuit. Second, means which will permit the doors to be opened and closed independently of the controlling means; which will enable all of several doors to be actuated by a watchman from a single point; which will enable the fire to automatically close one or more doors no matter where in 25 the building the fire may occur, and which can instantly close upon the outbreak of a slight blaze any conduit or chute leading to other parts of an establishment. Third, the invention relates to certain improvements in 30 details of construction hereinafter set forth.

Referring to the drawings forming part of this specification, Figure 1 is a sectional elevation of a building showing a plurality of floors and door ways controlled by electric devices embodying my improvements. Fig. 2 is a sectional elevation of a building showing a plurality of doors all closable automatically by a slight fire at any one point in the room. Fig. 3 is a diagram of a machine having a conduit adapted to be closed by a blaze which might be started by the machine itself.

In the structure illustrated in Fig. 1, the reference numeral 1 designates a door-way; 50 2, a fire-door therefor supported by wheels 3 running on an inclined rail 4; and 5, 6 and 7 are the floors of the building. This inclination of the rail 4 causes the door to roll to its closing position in front of the door-way 1, unless it is held wide open. For the latter purpose, an electromagnet 10 is at-

tached to a suitable support, as the wall pierced by the door-way, and an armature 11 is carried by the door. So long as the electromagnet is maintained in an energized 60 condition, its magnetic pull upon the armature serves to retain the door in its open position, since the amount of energy required for the purpose is comparatively slight, and since, moreover, the armature is 65 composed of soft iron.

For demagnetizing the electromagnet when a slight fire, or an unusually high degree of heat occurs at any part of the room, the conductor wires 12, by which the current 70 is delivered from a suitable source, as 13, to the electromagnet, are provided with numerous short sections 14 of easily fusible material distributed at frequent intervals therein.

Consequently, if a blaze or an extra high degree of heat occurs anywhere along the path of the wire, the fusible metal melts, the circuit is broken, the electromagnet is demagnetized, and the door rolls down to its closed position. By locating this wire at all exposed points on the walls, ceiling and elsewhere, it is made practically impossible for a fire started in one of the rooms to spread through a doorway to another part of the establishment. 75

I prefer to provide a stop 15 for the door 2 when it is thrown open, and to provide a spring connection 16 between the armature 11 and the door, in order to save the electromagnet from any shock during such openings, and at the same time to maintain the armature in absolute contact with the pole of the electromagnet and so to insure the maximum of attractive pull between the two. 80

The spring illustrated is a small elliptical one, but I do not restrict myself thereto, since any form of resilient buffer which will both sufficiently yield and at the same time confine the armature to the door, will serve 85 the purpose.

In the form of wiring disclosed in Fig. 1, a fire in one of the rooms may not close more than one door, that is, a fire in the upper room will open the circuit for that room's 105 door-holding magnet alone, and a fire which will fuse the sections 14 along the ceiling of the lower room will affect its door alone, but a fire below the floor 7 or at the walls of the lower room will effect the closure of both of 110 the doors.

For enabling a watchman to close both

doors simultaneously and without awaiting a heat-broken circuit, a switch 17 is introduced into the circuit at a convenient point, as in the wire-section 12^a of the upper room, 5 and the wire 12^b is connected with the wire 12^a above the switch. Thus arranged, a throw of the switch demagnetizes all the electromagnets and causes all the doors to close; after which, he returns the switch to 10 its closed position, in order that when the doors are slid wide open in the morning, or other desired occasion, they will all be magnetically held open. A voltmeter 19 may be provided for the purpose of revealing at 15 sight if the current supplied by the batteries, or other source 13, is sufficient for holding the doors.

In the construction illustrated in Fig. 2, a single room is shown having several doorways 1 provided with self-closing doors 2 held open by electromagnets 10. These electromagnets are all arranged in series so that if the circuit is broken at any point in the wires 12, all of the magnets simultaneously 25 release their armatures 11 and all the doors close.

Fig. 3 indicates a machine 20, supposedly one which is used in connection with highly combustible material, as cotton lint, and 30 from which a conduit 21 opens to other parts of the building. This conduit is shown as closable by a sliding door 22 actuated by a weight 23, the door being held open by an electromagnet 10 and armature 11. The circuit wire 24 is shown as disposed closely 35 about the mouth of the conduit 21 and about the machine, so that the instant a spark or overheated bearing starts a blaze in the cotton, the door is closed and danger of spread 40 of the fire reduced to a minimum.

Among other advantages of this system of fire protection are its economy, ease of installation, its guarantee against failure, and its convenience and durability. With this 45 closed circuit system, the moment a wire becomes accidentally broken, or the current source unduly weak, the same is revealed by the closing of the doors. A door can be closed by hand without affecting the mag-

netic devices and without stopping to disconnect any hooks or catches. Any watchman or attendant can, by the simple throw of a switch, close every fire door in the building or throughout the establishment, where previous to my invention it frequently required one or two hours for a watchman to journey from floor to floor and room to room closing the doors by hand. 50 55

While I have illustrated my invention as applied to sliding doors alone, I do not restrict myself thereto; nor do I restrict myself to doors normally held open by a magnet, as it is self-evident that the reverse can be done equally well. 60

In my use of the word "door" in the 65 claims, I wish to be understood as embracing therein all devices for inclosing openings, including shutters, blinds and the like.

What I claim is:

1. The combination with a fire door or 70 the like having continuously acting means for closing it, of an electromagnet and an armature one of which is carried by said door and the other of which is supported stationary with respect to said door, and 75 means controlled by variations in temperature for energizing said electromagnet, said electromagnet and armature being disposed to be brought together when said door is open and to hold the latter by direct mag- 80 netic attraction from the effect of said continuously acting closing means, while permitting its ready closure by hand.

2. The combination with a fire door or the like having a continuously acting means for 85 closing it, of an electromagnet supported near the door when the latter is open, an armature having a resiliently yielding connection with the door to be supported in the magnetic field of the electromagnet when the 90 door is open, means for continuously energizing the electromagnet, and means controlled by variations in temperature for cutting out the energizing means.

In testimony that I claim the foregoing 95 invention, I have hereunto set my hand this 28th day of July, 1917.

SIDNEY C. FISHER.
